(57) **CLAIM**

The ornamental design for a notebook computer with movable keyboard and palm rest, as shown and described.

DESCRIPTION

FIG. 1 is a perspective view of a notebook computer with movable keyboard and palm rest showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof with the display unfolded;

FIG. 9 is a top view thereof with the display unfolded;

FIG. 10 is a perspective view thereof with the display unfolded and the keyboard and the palm rest moved; and, FIG. 11 is a top view thereof with the display unfolded and the keyboard and the palm rest moved.

The dashed broken lines illustrate portions of the notebook computer with movable keyboard and palm rest and form no part of the claimed design.
